(57) **CLAIM**

The ornamental design for a neck reading light, as shown and described.

DESCRIPTION

FIG. 1 is a first perspective view of a neck reading light, showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of the neck reading light thereof, shown in an alternate configuration of use; and, FIG. 10 is an enlarged view of the selected portion 10 in FIG. 1.

The broken lines shown in the drawings depict portions of the neck reading light that form no part of the claimed design. The dot-dash broken lines in FIGS. 1 and 10 are for the purpose of annotating the enlarged views and form no part thereof.
